[57] CLAIM

The ornamental design for a combined lamp socket and globe holder for a suspended electric light fixture, as shown and described.

DESCRIPTION

FIG. 1 is a top plan view of a combined lamp socket and globe holder for a suspended electric light fixture embodying my new design;

FIG. 2 is a bottom view of the combined lamp socket and globe holder for a suspended electric light fixture as shown in FIG. 1;

FIG. 3 is a front view of the combined lamp socket and globe holder for a suspended electric light fixture shown in FIG. 1, a mirror image of the rear view thereof;

FIG. 4 is a right-side view of the combined lamp socket and globe holder for a suspended electric light fixture shown in FIG. 1;

FIG. 5 is a left-side view of the combined lamp socket and globe holder for a suspended electric light fixture shown in FIG. 1; and,

FIG. 6 is a cross-sectional view of the combined lamp socket and globe holder for a suspended electric light fixture shown along section lines 6—6 of FIG. 2.

FIG. 1

FIG. 2
